BRUSH

Frederick W. Curtis, Jr., Minneapolis, Minn.

Application March 12, 1937, Serial No. 130,540

3 Claims. (Cl. 15—122)

This invention relates to brushes and more particularly to a type of brush adapted to have associated therewith a cake of solid soap in such a manner that the soap and brush form a substantially unitary scrubbing unit.

One object of this invention is the provision of a brush of such character which will be relatively simple to manufacture and having a minimum production cost.

10 An additional object is the provision of a brush adapted to accommodate any one of a variety of sizes of cakes of soap in such a manner that the brush and soap as a unit may be utilized by a bather as necessary.

15 As conducive to a clearer understanding of this invention it may be here pointed out that numerous types of soap now on the market are of a sinkable or nonbuoyant character and tend therefore to become invisible under the surface of the 20 water during the bath of an individual. Additionally it frequently so happens that in bathing the operations of soaping and subsequent scrubbing of the body entail a needless and unnecessary exertion on the part of the individual.

25 It is an object of this invention to provide a bathing brush of such a character as to preclude all possibility of temporary misplacement or loss of the soap while bathing and further to provide a brush of such a character that the soaping and 30 scrubbing of the individual may be accomplished in a single operation.

35 A still further object of this invention is the provision of a brush which provides in and of itself a container of soap in such manner as to obviate the necessity of the provision of a separate drainage receptacle for soap at the termination of the bath.

Other objects will in part be obvious and in part pointed out hereinafter.

40 The invention accordingly consists in the combinations of elements, arrangements of parts and features of construction, all as will be more fully pointed out hereinafter and disclosed in the accompanying drawing, wherein:

45 Figure 1 is a side elevational view of a brush embodying the inventive concept.

Figure 2 is a bottom elevational view of the brush shown in Figure 1.

50 Figure 3 is a sectional view along the line 3—3 of Figure 2 as viewed from the top disclosing the brush having a cake of soap assembled in operative relation therewith,

55 Figure 4 is a side sectional view of a structure embodying a modified form of the inventive concept.

Having particular reference now to Figure 1 there is generally indicated at 10 a handle of any conventional design provided with a plurality of tufts of bristles 11 which may be secured thereto, as best shown in Figure 3, by insertion in suitable recesses 12 in the handle portion 10 of the brush.

5 Bristles 11 are arranged, as better shown in Figure 2, in the peripheral band about exterior annular edge of handle 11 so as to provide a suitable space or aperture 13 (see Figures 2 and 3), of 10 a size adapted to accommodate an average sized cake of conventional bath soap 25 (see Figure 3). The under surface of handle portion 10 is provided with a plurality of striations or corrugations 14. Corrugations 14 may, as best shown in 15 Figure 2, take the form of angularly disposed recesses 15 separating the under surface of handle 10 adjacent aperture 13 into a series of relatively large blocks 16. Blocks 16 are so formed as to provide relatively sharp protruding corners to 20 effect interengagement with a cake of soap when the same is placed thereupon and are of sufficient cross sectional area to preclude the possibility of inadvertent breakage of the same as would be the case were the blocks of smaller dimension. 25

A modified form of construction is shown in Figure 4 wherein a handle 10' accommodates a plurality of tufts of bristles 11' inserted in suitable apertures 12' the tufts of bristles being arranged in a peripheral band similar to that of 30 the bristles shown in the preceding modification. In the form shown in Figure 4 however, a slight recess 20 is cut into the inner surface of handle 10' and in recess 20 are disposed a plurality of pins 21 having enlarged heads 22 which serve a 35 purpose analogous to that of blocks 16 and grooves 15 of the previously discussed modification.

40 From the descriptions given above the operation of the device of the instant invention should be readily understood. Soap 25, as best shown in Figure 3, is inserted in aperture 13 and placed firmly therein in such manner that blocks 16 engage the upper or adjacent surface of soap 25 in such manner as to hold the same in related assembly therewith. After the soap is wet it will be readily understood that by the normal softening process occasioned to the soap by the solvent action of water the interengagement of grooves 15, blocks 16 and soap 25 will become relatively 50 fixed in such manner that the engagement will be maintained throughout the active period of existence of the soap before dissolution of the same. In case of the modification of Figure 4 a similar procedure is observed save that in this 55

case soap 25 is impaled upon pins 21, enlarged heads 22 of which serve to maintain the same in rigid related assembly therewith.

In the use of the device therefore the operator or bather need only position the soap in the manner above described and consequently utilize the brush in the normal manner incident to the use of scrubbing brushes whereby to effect a soaping and at the same time a scrubbing motion 10 with respect to the area so treated. It will be understood that soap 25 after immersion in water will act in the manner normal to soap and diffuse a certain portion of its exterior constituents to the surrounding tufts of bristles 11 in such 15 manner that the said tufts will become thoroughly impregnated with the solvent substance of the soap and thus effect a simultaneous soaping and scrubbing action upon the area so scrubbed.

20 It will thus be seen that there is provided in the invention hereinbefore described a bathing brush accomplishing the objects of this invention as well as others of great practical importance, it being understood that upon termination 25 of the bath the bather need not remove the soap 25 from receptacle 13 but may merely by positioning handle 10 upon a suitable surface provide an effective drainage receptacle for soap 25, the liquid residue of which, it will be understood, will 30 flow through the apertures between the tufts of bristles 11, thus obviating the necessity for a separate soap dish or other analogous receptacle. Additionally in the use of the brush as previously pointed out, it will be readily understood 35 that in one comparatively simple operation the bather may accomplish both the soaping and scrubbing actions normally requisite to bathing in a single simple operation.

While in the foregoing the brush of the instant invention has been described primarily as a brush adapted to be utilized for the bath, it will

be readily understood that the same may be used for a variety of purposes, as, for example, a floor or scrub brush, a brush for washing furniture or analogous articles, or a brush for the scrubbing of livestock.

As many embodiments may be made of the above invention and as many modifications may be made in the embodiment herein set forth and shown in the accompanying drawing, it is to be understood that all matter hereinbefore shown 10 or disclosed is to be interpreted as illustrative and not in a limiting sense.

I claim as my invention:

1. In a device of the character described, in combination, a handle portion, bristles secured to 15 said handle portion in a band forming an aperture for the reception of a pre-formed cake of soap, a surface of said handle portion exposed in said aperture having a plurality of transversely cut grooves therein forming rigid projections adapted to have said cake of soap im- 20 paled thereon to secure the same in related assembly to said handle and said bristles.

2. In a device of the character described, a handle portion, bristles secured in and projecting 25 outwardly from a surface of said handle portion in a band forming an aperture for reception of a preformed cake of soap, spaced rigid soap anchoring projections on the surface of the handle portion exposed in said aperture and extending 30 in substantially parallel relation to the surrounding bristles, said rigid projections being adapted to have a preformed cake of soap impaled thereon to secure the soap in related assembly to the handle and bristles.

3. The structure defined in claim 2 in which 35 said rigid projections have relatively small cross-sectional dimensions and are provided at their free ends with enlarged anchoring heads.

FREDERICK W. CURTIS, JR.
